UNITED STATES PATENT OFFICE

WILLIAM HUNTINGTON RUSSELL, OF NEW HAVEN, CONNECTICUT

STORE SYSTEM ACTUATED BY A COIN MACHINE

Application filed October 19, 1929. Serial No. 400,998.

This invention relates to a system whereby any number of different articles in a store may be purchased through the agency of a coin actuated vending machine by moving 5 the vending machine in front of, or in a pre-determined position in respect to the article to be purchased and then operating the machine through the agency of a coin. This is a basic invention and covers the novel idea 10 of moving a coin actuated machine in order to purchase an article located in a different place from the article last purchased. In this way a whole store system can, if desired be operated by a single machine regardless 15 of whether all the articles sell for the same price or at different prices. Moreover the prices of the articles may be changed as desired and still the machine may be operated to produce not only any article, but also give 20 the correct change for any coin of larger value than the price of the purchased article, when the coin is placed in the insertion slot of the machine.

One object of the invention is to obtain a 25 basic patent on the novel idea of moving a vending machine so that either one or more vending machines can operate a store system as desired even though the articles sold range in prices.

Another object of the invention is to sell 30 articles through the means of a coin actuated vending machine without the necessity of placing the articles to be sold in the machine. By placing the articles to be sold 35 outside of the machine the machines may be smaller than would otherwise be possible and a larger and more varied supply of articles may be sold.

Another object of this invention is to obtain 40 the same results from one machine which in other vending systems require a number of vending machines. In this way there is a considerable saving in the cost of installing this system over other coin vending systems 45 and each machine is smaller and easily moved.

Another object of the invention is to do away with clerks in stores, thereby saving 50 expense. By using this system whereby a customer pays the money into the machine

and then obtains the desired article and any change if due, not only is time saved but also the cost of operating a store system is lessened.

Another object of the invention is to provide 55 a system where paper bags, wrapping paper and string are carried on the machine itself. In this way customers will have either paper bags, wrapping paper or string whenever a purchase is made. By having the 60 article sold, the coin vending machine and paper bags all adjacent to the place where each purchase is made there is a considerable saving of time over old systems. In the present 65 store systems paper bags, the article sold and the cash register are often at different locations and it takes a considerable length of time for a clerk to wait on a customer for this reason. In this system a customer can make a purchase by himself or herself in a 70 very much shorter time than under the old system.

There are other objects one of which is to provide a stationary rod having holes at 75 spaced intervals along its length. This rod passes through the machine and regulates the amount of change to be deducted which corresponds with the price of the article sold.

In the accompanying drawings:

Fig. 1 is a plan view of the machine with 80 the casing removed to expose the interior mechanism, and a section of the store system operated by this mechanism.

Fig. 2 is a side view of the interior mechanism of the machine and store operated by 85 the machine.

Fig. 3 is a sectional view of the mechanism taken on the line 3—3 of Fig. 1, and the rods passing through the mechanism which regulate the amount of change to be deducted. 90

Fig. 4 is a sectional view on the line 4—4 of Fig. 2 showing the rod extending through the machine which regulates the number of pennies to be withheld in the penny magazines during the operation of the machine. 95

Fig. 5 is a fragmentary view of Fig. 4, but shows the parts held in a forward position.

Fig. 6 is a section on the line 6—6 of Fig. 3.

Fig. 7 shows the manner of returning deposited coins to the owner when the mecha- 100

nism is held in a forward position as shown in Fig. 5.

Fig. 8 is a section on the line 8—8 of Fig. 3 of parts of the mechanism.

5 Figs. 9 and 10 are sectional views through the operating mechanism to show the operation thereof.

10 Fig. 11 is a section of a hinged coin ejector which normally produces change unless deflected.

15 Fig. 12 is the same as Fig. 11 but shows the coin ejector deflected downward during its forward stroke by means of a pin inserted into a stationary rod passing through the machine.

18 Fig. 13 is a side view of a modified ejector which may be deflected sideways, and means for deflecting it.

20 Fig. 14 is a top view of the ejector shown in Fig. 13, and means for deflecting the same.

25 The coin actuated machine part of the store system which I have selected to illustrate and described as a preferred embodiment of my invention, is enclosed in the case 10, which is provided with a single coin slot 11, a section of which is shown in Fig. 2 through which the coins of all denominations are inserted. An operating handle 12 projects through the front wall of the case 10 by which the necessary power is supplied to cause the coin deposited to manipulate the proper mechanism disposed within the case. Operation of this mechanism delivers the required amount of change together with the article being vended 30 to the change hopper 13, from which it may be removed by the depositor of the coin.

35 The slot 11 formed in the casing 10, receives the deposited coin and directs it into a horizontally slidable coin receiving chute 14, which guides the coin in its downward movement into the mechanism. A pair of vertically disposed plates 15 and 16, which are spaced apart sufficiently to permit coins to pass therebetween, are disposed below the chute 14, with the passageway therebetween in alignment with the opening in the chute, and guides the coins during their further downward movement after the same leave the chute. Horizontally disposed openings 18, 18^a, 18^b and 18^c are provided in each of the plates 15 and 16 to permit part of the operating mechanism to extend laterally there-through, Fig. 9 and to form bearings for the upper surfaces of coin pushers 17, 17^a, 17^b and 17^c, Fig. 2.

40 The plates 15 and 16 are supported by being secured to uprights 19 and 19^a that are disposed one adjacent the outer side of each of the plates 15 and 16. The uprights 19 and 19^a are formed as a part of side frame members 20 and 21. The uprights 19 and 19^a are each provided with horizontally extending transversely aligned bar members 22, 22^a, 22^b and 22^c, in which slideways 23, 23^a, 23^b and 23^c that guide slides 24, 24^a, 24^b and

24^c, are respectively formed. A magnet 25 is secured to one of the upper bars 22 and extends toward the coin passageway between the plates 15 and 16, having its magnetized ends in alignment with one side of the passageway and being disposed between the chute 14 and the upper edge of one of the plates.

70 The passageway between the plates 15 and 16 is open from top to bottom and, therefore, any coin that is deposited may drop therethrough on to a transversely extending tray 26, Fig. 2 disposed below these plates. The tray 26 is set at an angle to cause the coins received thereon to slide downwardly toward one side of the casing 10. A bar 27 hinged 75 at one end to the adjacent frame member is adapted to swing across the lower end of tray 26 and retain the coin received thereby at this point. A window is provided in the side of the casing 10, adjacent the lower end of tray 80 26, permits one to ascertain what type of coin was last deposited. The bar 27 being swingable may be moved into coin releasing position when the mechanism is subsequently operated to permit the coin retained thereby to 85 drop into the bottom of the casing or into a coin receiving receptacle 29 placed beneath the same, as indicated in dotted lines in Fig. 2.

90 The coin pushers 17 to 17^c inclusive, extend through suitable openings in the front wall of the casing 10 Fig. 3 and are secured together at their outer ends by a vertically disposed bar 30 to which the handle 12 is secured. A guide opening 31 is located within the plates 15 and 16, and by means of the 95 formed openings therein forms a guide bearing for these pushers. The handle may be designed so that the arms 17 to 17^c inclusive may operate entirely within the casing and only the handle 12 and its two arms 12^a operate 100 outside the casing.

105 The inner ends of the pushers 17 to 17^c inclusive, extend over and rest freely upon the slides 24 to 24^c inclusive, and are provided at these ends with notches 36, 36^a, 36^b and 36^c 110 respectively, shown more especially in Figs. 9 and 10. These notches embrace the edge of the coin and as will be hereinafter explained, push the coin forwardly in the machine to actuate one of the slides to operate 115 the machine.

120 The pushers are also provided with lugs 37, by which coins or slugs that might be too large to enter the coin opening in any of the slides will be returned to the depositor. Such coins, when deposited would assume a position such as shown in dotted lines in Fig. 9, and during the forward movement of the pusher would be raised out of their respective slots and strike and be held by a 125 stop pin 38, and, therefore, roll up over the lug, as illustrated in Fig. 10, whereupon during the outward movement of the pushers, this coin would be pulled forwardly and permitted to drop through the opening at the 130

end of the plates 15 and 16 into the change hopper 13, Figs. 2 and 3.

The lug 37, upon the upper pusher 17, is disposed adjacent to its rear end and instead of operating, as above explained, will push a slug or other imitation coin rearwardly to cause it to drop within the casing, and not be returned to the depositor. The lug 37 will also wipe off any metallic washers or the like, that have adhered to the magnet 25, and deposit them within the casing for a purpose to be hereinafter described.

As shown more especially in Fig. 3, the slides 24 to 24^c inclusive, which are movably mounted in the slideways 23 to 23^c inclusive, are provided with coin openings 39, 39^a, 39^b and 39^c respectively, which are graduated in size to provide for each denomination of coin which the machine is designed to handle, the largest opening 39 being in the top slide 24. The effective size of these openings may be very finely adjusted by means of small leaf springs or the like 40, 40^a, 40^b and 40^c, which are adjustably mounted upon the lower faces 25 of the slides so that they may be moved in a direction to cause their ends to project over the sides of the coin openings and limit the size of these openings. These springs are secured adjacent their rear ends to the slides 30 so that the front end of the spring may spring away when a slug or disk which is heavier than the legal coin of that size, such as a lead slug, for example, is inserted in the machine and cause such slug to drop through 35 the opening before the mechanism can be operated. The front end of the spring will be depressed and pass a proper coin through the machine after it has been operated in a manner to be hereinafter described.

40 Coin containers 41, 41^a, 41^b, 41^c, 41^d, 42, 42^a, 43 and 44 are provided, each comprising a tubular member adapted to be supported at one end and to extend upwardly in a vertical position. The containers 41 to 41^d inclusive in 45 this instance, are of the proper size to receive pennies, the containers 42 and 42^a to receive nickels, container 43 to receive dimes and the container 44 to receive quarters, the respective coins being received and contained there- 50 in one on top of the other. A suitable cross-bar 45 supports all of the penny containers 41 to 41^d inclusive, while the nickel and dime containers on one side of the machine are supported upon one cross-bar 46, and the 55 corresponding nickel and quarter containers on the other side of the machine are located on the support 46^a. Beneath each coin container a coin support is provided, such as a strip of metal 47, Fig. 2 which is secured 60 to the respective cross-bar, the support 47 for the penny containers being shown in Fig. 3. The lower end of each container is spaced from the corresponding coin support 47 an amount slightly more than the thickness of 65 the coins contained therein. For reasons ex-

plained later it may be an advantage for these coin containers to be spaced at unequal distances from each other when operating a store system and this may be done whenever desired.

70 Slidably mounted near each coin support 47 is a coin ejector, comprising a thin strip of metal capable of passing between the support 47 and the adjacent end of the coin container to engage and eject coins one at 75 a time from the container and off of the support 47, shown in Figs. 2 and 3 to permit them to drop upon a tray 48 down which they 80 may slide into the hopper 13. In this instance, coin ejectors 49, 49^a and 49^c and 49^d are provided for ejecting the pennies, 50 and 50^a for ejecting the nickels, 51 for ejecting the dimes and 52 for ejecting the quarters. The coin ejectors 49 to 49^d inclusive, are each 85 hinged near their center and each is riveted near one end to a strip 53. The coin ejectors 50, 51, 50^a and 52 are likewise hinged near their center and are fastened near one end to their supports. Each ejector has a spring 100 which normally holds both parts of the hinged 90 ejector in a straight line as shown in Fig. 11. Each ejector is normally held in position to eject a coin from its adjacent coin container, but by exerting a force against its coin ejecting top side during its forward movement 95 in a downward direction, the front end of said ejector will be directed at such an angle that it will not eject a coin when the machine is operated as shown in Fig. 12. This will 100 be more fully explained later in connection with operating the store system and deducting the amount of change equal to the price of the article purchased. The ejectors will act in unison to eject a coin from each of the respective containers 41 to 41^d inclusive, 105 or from any of the same wherein coins have been placed unless one or more is moved out of alignment with its corresponding coin containers by coming into contact with a deflecting means during its forward movement. The coin ejectors 50^a and 51 for ejecting a nickel and a dime respectively are normally operated together as they are controlled by the same operating mechanism and 110 will eject coins from the respective containers 42^a and 43. The other coin ejectors 50 and 52 operate separately to eject the proper coin from its container. The coins ejected from containers 42, 42^a, 43 and 44 are directed into the tray 48 by means of chutes 115 72 and 73, disposed in position to receive the same from the containers, both of which is shown in Fig. 4.

120 The coin ejectors are operated by the operating handle 12, due to the cooperation of the deposited coin with the proper slide therefore, and the action of the corresponding pusher thereon. The mechanism illustrated is not designed to operate when a penny is deposited, although it might have been. The 125 130

denomination of the smallest coin which will operate the mechanism illustrated, is a nickel, therefore the slide 24^b which is adapted to receive a nickel in the opening 39^b therein will be connected to the penny ejectors 49 to 49^d inclusive, so as to eject the proper change for the nickel deposited. Connection between the slide 24^b and the ejectors 49 to 49^d inclusive, comprises a pair of rods 54 which are secured at one end to the slide 24^b and at the other end to the strip 53, Fig. 8. The coin ejector 50 is connected by means of a rod 55 to the slide 24^c, which is adapted to receive a deposited dime in the opening 39^c therein, Figs. 2 and 8. The slide 24^c is arranged to engage the rods 54 and therefore will cause the operation of the penny ejectors 49 to 49^d inclusive, when the slide 24^c is operated. The coin ejectors 50^a and 51 are each connected to the quarter receiving slide 24^a by rods 56 and 57 respectively, and during their operation the downward extension end of rod 57 engages in back of and against the slide 24^c to operate the ejector 50 and also the ejectors 49 to 49^d inclusive. The coin ejector 52 is connected to the half-dollar receiving slide 24 by a rod 58, and during its operation the slide 24^a is engaged by a depending member 59, also secured to the slide 24 to operate the ejectors 50^a and 51, 50 and 49 to 49^d inclusive, due to the inter-engaging structure above described, Fig. 8.

Secured to the strip 53 and under the control of the rods 54 is a pair of parallel elongated article ejector rods 61 and 62 which extend out of the machine. The outer ends of the rods 61 and 62 extend into the store system and these rods are bent and joined at their ends adjacent to the bottom row of articles to be sold. When the machine is opposite an article to be purchased and the machine is operated, the extension of these rods 90 where they are joined together, Fig. 2, will 45 come in contact with the lower article and by raising its lower end over its base support 92 will cause the article to fall into the chute 93 which runs the length of the store, and be delivered to the hopper 94 located in 50 a convenient position under the machine and along the store. The purchaser can then take the article from the hopper 94. The rods 61 and 62 are in a position to reach the articles in the store when operated by the 55 coin changing machine. They move along the opening in the partition whenever the machine is moved as described below. The rods 61 and 62, and their projections 61^b and 62^b are adapted to enter through suitable 60 openings 114 between the partition which separate the articles in the store from purchasers, Fig. 1. These article ejector rods engage any article contained therein and eject it therefrom through an opening 93^a, 65 thereby causing it to drop into the chute 93

and be deposited into the hopper 94 when the machine is moved to a predetermined position in reference to the article to be purchased. Another rod 60 having one end pivotally attached to the strip 53 between the 70 rods 61 and 62, during its operation, rides upon the periphery of coins in the coin or disk container 41^b, an opening 65 being provided in the wall of this container to permit this action. A catch notch 66 is cut in the 75 rod 60 and properly disposed therein to catch against the edge of the opening 65, to prevent the return of the rod 60. The penny-ejectors 49 to 49^d inclusive, when the coins or disks in the container 41^b are exhausted will remain 80 in their forward position as they are fastened to and operated by the same means as the rod 60. (See Fig. 4.) A spring 67 is disposed between and secured to each of the rods 60 and 62, to insure that this action takes place, 85 the rod 62 being retained against lateral movement by means of a stop lug 68 on the container support or cross-bar 45. By this arrangement the article ejecting rods and penny-ejectors are prevented from returning 90 to their normal position, and therefore the slide 24^b is retained out of coin receiving position relatively to the slot 11.

To prevent the deposited coin from entering the mechanism when the coins are exhausted from the tube 41^b, or nearly so, the 95 slidable coin receiving chute 14 is connected to the slide 24^b by means of a rod 69. Being so connected, the chute 14 is moved at each 100 operation of the mechanism into the position shown in Fig. 7. This action will present a guard plate 70, which is connected to the chute 14, into a position below the slot 11. A subsequently deposited coin will therefore 105 drop upon the plate 70 and be deflected due to the angle at which the plate is set into a trough 71, which is connected to the frame 20, and be directed away from the mechanism to permit it to drop into the hopper 13, thus returning the coin to the depositor. In 110 this manner, after the mechanism is locked by means of the catch 66, as above described, all coins deposited into slot 11 will be returned to the depositor.

Suitable springs are provided for returning the slides to their normal positions in which the openings therein will be in alignment with the chute 14. For this purpose, springs 74 and 75 secured to the lower pusher 17^c and respectively to the slide 24^c and a 120 forwardly directed extension 53^a of strip 53, are provided. When the handle and pushers are pulled outwardly, springs 75 and 74 act to return slides 24, 24^a and 24^c, and the nickel, dime and quarter ejectors, spring 76 125 returning the slide 24^b, the chute 14, guard plate 70 and trough 71, and the penny and article ejectors. By means of separate springs, the parts controlled by spring 74 and 75 may return, even though the remain- 130

ing parts controlled by spring 76 are retained, due to the exhaustion of coins or disks in container 41^b. The spring 76 is connected to the extension 53^a, and at 77 to one of the upright frame members. The spring 76 stretches when the penny ejectors are forced inwardly and therefore pulls upon a cord 79, which is attached to the bar 27, raising it to allow the coin which has subsequently been used to operate the mechanism or has been rejected as aforesaid to drop into the container 29. The return of the penny ejectors and the extension 53^a, releases the bar 27 and permits it to drop into position to act as a stop, as previously described.

The coins retained in the openings 39 to 39^c inclusive, in the respective slides, are attacked by the proper pusher within the grooves in the ends thereof, whereby the mechanism is operated. For instance, referring to Figs. 9 and 10, a deposited coin drops into the opening 39^b in slide 24^b and is retained against dropping therethrough by the leaf spring 40^b. The pusher 17^b is advanced and engages the coin to force the slide inwardly. If the coin is a proper one, it passes below the stop pin 38 and engages a swingable pawl 80, which is adapted to freely raise to permit the coin to pass thereunder in an inward direction. After the coin has passed the pawl 80, the same swings downwardly and is stopped by the stop pin 38, and blocks the return of the slide and coin unless the coin has been forced through the opening in the slide. Any attempt to return these parts before this action has taken place, therefore, will be frustrated. Each of the pawls 80 is provided with a cam edge 81 which will cam the coin through the opening in the slide against the tension of spring 40^b if the inward stroke of the pushers is not entirely completed. At the completion of the inward stroke of the pushers the coin is cammed through the opening in the slide by a camming lug 82, provided upon the side plates 15 and 16. The pawls 80 may be so shaped as to do away with the cam edge 81 if desired. The coin will not then be removed until cammed by the cam 82.

In this instance, the upper pawl 80^a is not provided with a cam edge, but swings into the position shown in dotted lines in Fig. 3, and acts as a continuation of the camming lug 82^a. The upper stop pin 38^a, in this instance, does not interfere with the coins, as previously described, relative to the stop pins 38, but permits coins to pass thereunder whereby of the coin deposited is an imitation one, or too large to pass through the opening 39, in slide 24, it will be pushed off the slide by lug 37 placed near the end of the pusher 17 and will fall within the device and not be returned.

The camming lugs 82 are provided with upwardly directed surfaces 83, that are dis-

posed at an angle to the horizontal and directed downwardly toward the rear of the mechanism. This arrangement causes these lugs to act as guides upon which the coin forces through any of the slides above will strike and be deflected to the rear as not to be caught or lodged in the mechanism therebelow, but will drop directly into the tray 26.

It will be understood that in the present instance, the opening 39 in slide 24 is adapted to receive half dollars, the opening 39^a in slide 24^a is adapted to receive quarters, and the opening 39^c in slide 24^c is adapted to receive dimes. As all of these openings are in alignment with the chute 14 and slot 11, any coin deposited in the slot 11 will drop downwardly through the machine and enter the opening designed to receive it.

Assuming that a nickel is deposited, the same will drop downwardly through the mechanism and rest in opening 39^b in slide 24^b, and upon operation of the handle 12, to thrust the pusher 17^b inwardly, will act upon all the penny coin ejectors 49 to 49^d inclusive, with the article ejectors 61 and 62 to deliver one coin or penny from each container 41^a, 41^b and 41^c, etc. together with the article being vended as is described in detail below into tray 48 and thence to hopper 13. At the completion of the stroke, the nickel deposited will be forced through the opening 39^b by the cam lug 82, and will fall into tray 26 and be directed into a container 29. When the machine is moved on its wheels along the tracks to a position where it will not purchase an article the machine may be used as a coin changer and will give full change for any coin inserted.

When a dime is deposited, due to the connections described above, the coin ejector 50 will be operated to eject a nickel from the coin container 42, in addition to the three pennies and the article which we are assuming sells for two cents. When a quarter is deposited, coin ejectors 50^a and 51 will be operated to eject another nickel and a dime from coin containers 42^a and 43 respectively, in addition to the nickel, three pennies and the article. When a half dollar is deposited coin ejector 52 is operated to eject a quarter from the coin container 44, in addition to the aforesaid coins and article.

When the article is to sell for 5¢, the penny containers 41, 41^a, 41^c and 41^b will not produce change due to the deflecting of the penny ejectors as is fully described below. When such an arrangement exists, an article will be delivered when a nickel is deposited, an article with a nickel from the container 42 when a dime is deposited, two nickels and a dime from containers 42, 42^a and 43 when a quarter is deposited, and a quarter, two nickels and a dime from containers 44, 42, 42^a, and 43 when a half dollar is deposited.

The coins in container 41^b may be allowed

to fall into the tray 48, if this action is desired or they may be directed down a supplemental chute 84 and into tray 26. The supplemental chute 84 shown in Figure 3 extending from under the container 41^b into the tray 26 carries the coins from only the container 41^b into the tray 26. As is explained elsewhere, the container 41^b and the supplemental chute 84 serve the purpose of keeping the machine from being operated after coins in the various containers have been almost depleted. If the supplemental chute 84 is removed coins will enter the hopper 13 whenever ejected from the container 41^b. The supplemental chute only serves the purpose of collecting coins from the container 41^b for the owner of the store.

For instance, if the price of any article is five cents then no pennies will be produced from any of the penny containers except 41^b. As this penny must not be given in change, the supplemental chute is necessary to carry this penny into the tray 26. If the price of an article is four cents then the supplemental chute is not necessary as this penny is given in change. All articles for sale must be priced so as to either use the supplemental chute 84 and collect a penny for the owner each time the machine is operated, or not use the chute 30 and collect the penny from magazine 41^b in change for the customer. In either case a coin must always be obtained from magazine 41^b as this regulates the number of times the store system can be operated without danger 35 of not giving change to a customer when any of the change magazines are empty, as elsewhere explained.

As pointed out above, if slugs or the like are deposited and attracted by the magnet 40 25, or are too large to enter the opening 39 in slide 24, they will be pushed off the same by the lug 37 and caused to drop into tray 26, and slugs or imitation coins that are not attracted by the magnet but are too large to 45 properly enter any one of the openings 39^a to 39^c inclusive, will be pulled forwardly by one of the lugs 37, to drop into tray 48 and hopper 13, the stop pins 38 preventing these slugs from being moved rearwardly 50 and causing them to ride up and over the lug. The coin last deposited and used to operate the mechanism or rejected by the lug 37, may be observed through a window in the casing as it rests upon tray 26, being retained thereon by bar 27, and therefore, should a claim 55 be presented that a legal coin was deposited and was retained without the machine operating, the exact nature of the deposited coin or the like could be detected. When the container 41^b has been almost depleted of coins 60 the deflector 70 is held under the slot 11 so that the inserted coins are deflected into the channel 71 and returned to a prospective purchaser, thereby giving notice that the machine 65 cannot be operated. By this arrangement

of the parts, the rod 60 will be permitted to swing toward the coin or disk container 41^b, when the coins therein are exhausted whereby the catch 66 will engage upon the edge of the opening 65 in the wall of this container, 70 and therefore, if the same or a lesser number of coins are placed in the container 41^b than the articles to be sold or coins in other change containers, a positive action is thereby obtained to lock the mechanism and deflect coins inserted in the slot by means of the deflector 70 in the chute 71.

While I have shown and described a preferred embodiment of the coin changing part of my invention, it is understood that it is not to be limited to all of the details shown, but is capable of modification and variation which will lie within the spirit of the invention and the scope of the appended claims.

Before showing the manner of operating the store system in connection with the coin changing device described above, I want it understood that this store system may be operated by each and every machine which can be used in connection with this store system and is not limited to the device described above.

I want it further understood that this store system may be operated by movable electric machines which will operate by means of pressing a button or other starting device, or an electric device may be started and operated as a result of completing an electric circuit through a coin inserted into the device. I claim every store system described below 100 which may be operated by means of moving the article producing or obtaining device in front of, or in a predetermined position in respect to the article to be purchased which is located outside of the coin changing mechanism. Moreover, as many articles sell for the same price, I claim as a basic invention the novelty of moving the purchasing system or article producing means in a predetermined position in respect to the article to be obtained. This purchasing system may be any device and is, therefore, not limited to coin changing machinery.

I will now describe the store system in connection with the preferred coin changing device above described. The vending machine which operates the store system and which I have selected to illustrate and describe as a preferred embodiment of my invention consists of four sets of supporting wheels, attached to the underside of said vending machine, one set near each of its corners. Each of the sets consists of an upper wheel 117 and a lower wheel 118 so designed that all the wheels move in the same direction when operating along two tracks. The said two tracks are shown in Fig. 3 and each track extends between the upper and the lower wheel of two sets of supports so that the vending machine is movable along said tracks which are par-

allel as shown in Fig. 3. In this way the coin operated vending machine described above may be easily pushed along the tracks 119 and 119^a in either direction or stopped in any position desired. A rod 94 extends 5 through the machine and then extends outside of the machine, and along the entire store system in a direction parallel to the bottom articles in the store system and the tracks 119 and 119^a. A second rod 96 parallel to the rod 94 passes through the machine at 97 and is securely fastened at both ends so as to be parallel to rod 94. Both rods 94 and 96 are immovably attached near their ends to the 10 store system.

Each of the rods 94 and 96 have a number 15 of screw holes 98 through them in somewhat corresponding positions, at short intervals, Figs. 11 and 12. The screw holes 98 are spaced at intervals along the entire 20 length of one side of the rod 94 so that there are five screw holes on the rod 94 within each space required by the five penny coin magazines located in the machine. Whenever the 25 coin changing machine is in a position directly in front of any article to be sold in the store, a hole on the rod 94 will always be in an adjacent and corresponding position with each penny magazine, because this rod 30 passes through the machine a short distance above and in front of the hinged penny ejectors 49 to 49^a. As the coin changer is moved along its tracks in front of different articles to be purchased there will always be a screw 35 hole in front of each penny magazine before a purchase can be made due to correctly aligning the rod 94 through the machine and spacing each set of five screw holes on the rod 94, within a distance equal to the distance 40 between each corresponding article to be sold. If the space between the penny magazines varies, then the space between the screw holes on the rod 94 will also vary in exactly the same way. The 45 distance between screw holes on the rod 96 may also vary. The rod 96 passes through the machine parallel to the rod 94 and in a corresponding position to the coin ejectors. There are sets of four screw holes on the rod 50 96 at each corresponding interval of distance in which there are five screw holes on rod 94. There will be two screw holes on rod 96 opposite the center of the nickel and dime magazine on one side of the coin machine at the 55 same time that two screw holes will be in a similar position on the opposite side of the machine in front of the nickel and quarter magazine. The relative positions of coin magazines and rods are shown in Figs. 1 and 60 4, and the relative positions of the rods and hinged ejectors is shown in Figs. 11 and 12. Whenever the machine is moved directly opposite any article to be sold there will be a screw hole on each rod 94 and 96 in a pre- 65 determined position in relation to each adjacent coin change magazine. When it is desired to deduct one more pennies in purchasing an article one screw 99 shown in Figs. 11 and 12 is inserted in each screw hole 98 which is adjacent to the penny magazine from which a 70 penny is not to be given in change when the machine is operated. Whenever the coin changer is moved in front of any particular article the screw 99 will always be in the correct position to come in contact with and 75 thus divert downward the forward part of the coin ejector with which it comes in contact during the operation of the machine, so as not to produce a penny. When the front part of the coin ejector 101 assumes the position shown in Fig. 12 it will go under its coin container during its further movement forward. When the coin changer is moved to another position where the ejector is not interfered with, the spring 100 will place it 80 in alignment to produce a coin from its coin magazine, as shown in Figs. 1 and 4. The projection 103 fastened to the rear of the hinged coin ejector extends over part of the forward extension 101 thereby preventing the 85 spring 100 from raising the forward extension 101 beyond a line parallel to the projection 103.

By inserting a screw in a screw hole on the rod 96 in a correct location any coin may like- 90 wise be held in the containers 42, 42^a, 43 and 44 and not given in change during the operation of the machine. In like manner any coins may be withheld in any coin magazine during the operation of the machine in mak- 95 ing a purchase by placing a screw 99 in a hole located in the correct position both in relation to the purchased article and the coin magazine from which no change is to be given during the operation of the machine. The 100 rod 94 may control the withholding of one or more pennies in the five penny magazines during the operation of the machine due to the fact that the rod 94 extends through the machine in a position to always have holes 105 spaced at the right intervals to obtain this result, before an article in the store system can be obtained by means of extensions 61 and 62 from the machine coming in contact with the article to be delivered to the customer dur- 110 ing the operation of the machine by the agency of an inserted coin as described above. It is only a question of inserting screws in holes on the two rods 94 and 96 in positions where they will operate to withhold change 115 in the magazines equal in value to the price of each article in the store system. It is, of each article in the store system. It is, ther- 120 therefore, only a question of locating screws in holes on one or both rods 94 and 96 in pre- 125 determined positions in relation to the arti- cles in the store so as to withhold the proper amount of change when the machine is oper- ated. The screws will in this way bring 130 about the deduction of change of an equal

value to any purchased article. By removing or adding one or more screws in predetermined positions the price of any article may be changed as desired.

5 These screws are inserted in the screw holes which are directly opposite the article to be purchased. Whenever the machine is moved to a new predetermined position in front of any article to be 10 purchased in the store system, there will be a corresponding screw hole in the rod 94 for each penny coin container 41, 41^a, 41^c, 41^d and 41^b located within the machine. The tracks 119 and 119^a are stationary and parallel, and likewise the rods 94 and 15 96 are held in a parallel position to the tracks by supports located in any desired position within the store system.

When the machine is moved along the 20 tracks 119 and 119^a, in either direction in front of the article to be purchased any screw 99 Fig. 12, which has been inserted in a screw hole 98 in the rod 94 will push the end of a penny obtaining ejector which comes in contact with it out of position so that a penny 25 will not be obtained as change during the operation of the machine from that penny magazine. In this way a certain number of pennies may be deducted when the machine 30 is operated. In like manner when it is desired to deduct nickels, dimes, etc., screws are inserted through screw holes in rod 96 which are directly opposite or in a predetermined position to the article to be purchased, 35 so that these will likewise deduct the required amount from the nickel magazine, dime magazine, second nickel or quarter magazine as desired, by coming in contact with the coin obtaining ejector which is in front of that 40 particular coin magazine where money is not required as change, and pushing the said coin obtaining device so that it will not strike the lowest coin in its respective magazine, but will be directed under it. It is only necessary 45 to place a screw in the right hole in reference to the article to be purchased. Whenever the machine is moved directly in front of any article any particular coin magazine can be regulated to withhold all its 50 coins as the bottom coin will not be obtained due to the fact that the end of the coin ejector has been deflected.

Screws are inserted through the bottom of the rod 96 but if it is desired to deduct from 55 the quarter or nickel containers 44 or 43, and they are of higher elevation than the nickel and dime magazines on the other side of the machine, the screws controlling the ejection of the coins from the containers 44 and 43 60 are inserted through the top of rod 96 and extend upward to raise the nickel and quarter container controls which are constructed so that they may be raised instead of lowered. This arrangement allows a greater number 65 of different articles to be sold within the same

space. By inserting screws whenever desired along the whole length of the rods 94 and 96 in places directly opposite the article to be sold and in accordance with the desired amount of change to be deducted as explained 70 above, the price of an article may be regulated and correct change obtained for any coin of larger value inserted into the machine.

Having described the manner by which change is deducted, or obtained when not required to be deducted in accordance as the price of any article to be sold relates in value to the coin used to make a purchase, I will now explain how the articles are also obtained in this store system when the machine is 80 moved in a position directly opposite each article. The extensions 61 and 62 in front of the machine will extend within a short distance of any article to be sold when the machine is moved in front of, or in a predetermined 85 position to any article. These extensions are bent and so shaped that they will extend within the partition 105 which is U shaped and extended along the store system, but under the glass partition 107 through 90 which the goods in the store are seen by prospective purchasers. In this way goods cannot be obtained by purchasers without properly operating the machine in front of any 95 desired article, as only the extensions 61 and 62 can come in contact with any article. Goods are protected by means of the partitions 105, 107 and 106 as shown in Fig. 2. Each article for sale and its price label may 100 be seen through the glass window 107.

The goods to be sold are arranged in parallel rows on an inclined support 108 shown in Fig. 2. The support 108 has a small extension 92 along its bottom which will extend above the support 108 and keep the lowest article from sliding out of the support 108 until raised by the extensions 61 and 62 a sufficient height to slide over the support 92 and then down the incline 93 into the hopper 94. Between the glass partition 107 and the partition 106 is an open space 114 extending the entire length of the store, through which the article ejectors 61 and 62 extend, shown in Fig. 2. The goods to be sold are placed on the inclined support 108 according to their classification in parallel rows extending from top to bottom with partitions between them as shown in Figs. 1 and 2. The same kind of goods are placed one above another end to end so that when the lowest article of one classification is pushed up by means of the extension 90 on the ejectors 61 and 62, which are fastened together at their ends by the extension 90, Fig. 1, the next like article which is above will slide down and take the place of the article last pushed up by the extension 90 and delivered to the purchaser. The purchased article will slide down the incline 93 and into the hopper 94. A clerk may go behind the articles through a suitable door and 110 115 120 125 130

replenish the supply of any kind of article. The ejectors 61 and 62 have an upright stop 125 a short distance from the extension 90, which will not allow any article raised by the 5 extension 90 to fall into the chute 93 until the extensions 61 and 62 have been returned a short distance. Even though the extensions 61 and 62 are locked in their forward position due to the fact that the container 41^b has been 10 depleted of coins, nevertheless the extensions 61 and 62 will move back a sufficient distance to allow the raised article to fall into the chute 93; but due to the fact that the extension 90 has returned a sufficient distance so that it 15 will not again touch an article on the shelf, no other article will fall into the chute 93 except the article which has already been purchased.

Part of the extension rods 61 and 62, shown 20 in Fig. 1 will move in a forward position during the operation of the machine in making a purchase, and will pass within the slot 98^a in the partition 107 when in a forward position. There are similar slots 98^a opposite 25 each kind of article for sale in the store system. Should the machine jam so that the rods 61 and 62 will remain in a forward position, or should any coin magazine be depleted 30 of coins so that the rods 61 and 62 could not return to their normal position, then these bends 61^b will remain within two of the slots 98^a. Should anyone attempt to move the machine when the rods 61 and 62 are in this position the rods 61 and 62 will prevent this movement, as the slot 98^a will not allow a side 35 movement. In this way a side strain on the end of the extensions will be avoided.

When all the articles operated by one machine in the store system sell for the same 40 price, the rods 94 and 96 are not necessary as the machine may be regulated to give the proper amount of change for any coin of sufficient value to make the purchase by only placing coins in the coin containers from 45 which change is desired to be given when a purchase is made, and leaving the other coin containers empty.

Figs. 13 and 14 show a modified form of 50 coin ejector which may be moved sideways by coming into contact with a pin 120 on either of the rods 94 or 96. A spring 115^a normally holds the ejector in a position to produce change. When the ejector has been moved to one side during its forward movement the 55 spring will return it to its normal position when not acted upon by the pin 120. The ejector turns on a pivot 116^a when acted upon by any side force and is shaped with a point 60 so as to be deflected by the pin 120 in either direction.

Although I have only shown two kinds of 65 coin ejectors, there are many other kinds of ejectors and I claim each and every ejector suitable in connection with these machines.

To operate the machine and make a pur-

chase it is only necessary to slide the machine in front of the article to be purchased or in a predetermined position in respect to its location, and insert into the machine through the insertion slot a coin of larger value than the 70 article to be purchased. The coin will then operate the machine when purchasing an article which is less than the value of the coin inserted as described above. During the 75 operation of the machine the extension 90 on the rods 61 and 62 will exert pressure on the underside of the lowest article they come in contact with in such a way that this article which is on the bottom row, will be raised so that its lowest end is above the extension 80 92. The lowest end of the purchased article will then slide down the chute 93 and be delivered to the purchaser, in the hopper 94 located under the handle of the machine. The 85 correct change, if any will be found in the hopper 13 of the machine.

By moving the coin machine along its supports in either direction to a position in front of the article to be purchased and operating the machine by a larger coin than the value 90 of the article to be purchased, any lowest article in the store system may be delivered to a purchaser and also change when due. The top of the machine may act as a counter to carry any articles first purchased. When 95 the articles are obtained a paper bag may be found on the machine in any convenient rack as well as string and wrapping paper for the convenience of the customer.

I do not limit myself to any special method 100 of withholding the bottom coin in a coin magazine during the operation of the machine as there are many ways of obtaining this result. I claim each and every method 105 of accomplishing the regulation of withholding or giving change from any magazine when change is given or withheld from a magazine due to the position of the machine in which a coin magazine is located. Moreover, I 110 claim every way of controlling the means of giving or withholding coins in a coin magazine located in a movable coin changer when acted upon directly or indirectly as a result 115 of a rod extending through the machine. The coin changing machine may be moved or operated on any kind of supports and moved in each and every position desired in reference to each article in the store. I claim every 120 kind of store system where any article is obtained by means of moving and operating a machine in a predetermined position.

What I claim:

1. In a store system, a partition provided with a slot; a plurality of magazines on one side of the partition for holding articles, 125 means for supporting the magazines with the delivery ends of the magazines equidistant from the partition, a coin controlled mechanism on the other side of the partition, means movable parallel to the partition for sup- 130

porting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

3. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition along tracks for supporting the coin controlled mechanism, means mounted in said coin controlled mechanism for ejecting an article from any one of the article magazines and extending through the slot in the partition, coin

magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

4. In a store system, a partition provided with a slot extending horizontally along its entire length; an article slide on one side of the partition provided with division members forming magazines and having article holding devices extending above its lower surface, means for supporting the slide with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

5. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, U shaped rods extending under the partition and joined together near their ends mounted in said coin controlled mechanism for ejecting an article from any one of the article magazines and extending through the slot in the partition,

- coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines. 5 70 75 80
6. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the 20 article magazines and extending through the slot in the partition, coin magazines for holding change mounted in said coin controlled mechanism, hinged ejectors mounted in said coin controlled mechanism for ejecting coins 25 90 95 100 105 110 115 120 125 130
- 30 35 40 45 50
- 35 from the coin magazines, a fixed rod mounted parallel to the partition and extending through said coin controlled mechanism in front of the penny ejectors, a similar fixed rod in front of the nickel, dime and quarter ejectors; adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines. 40 45 50
7. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins 55 60 65 70 75 80 85 90 95 100 105 110 115 120 125 130

- through said coin controlled mechanism, removable pegs mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

10. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, holes at spaced intervals and means removably inserted in one or more selected holes on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

11. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, a lug on the article ejecting means for engaging during its forward movement with a slot in the partition and thereby preventing the moving of the coin controlled mechanism to a new position, coin magazines for holding change mounted in said coin controlled mechanism hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

12. In a store system, a partition provided with a slot; an inclined shelf on one side of the partition for holding different kinds of articles, division members on said shelf forming magazines for holding the articles in parallel rows, extensions on the shelf for engaging the lowermost article in each row, means for supporting the shelf with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

13. In a store system, a partition provided with a slot; a plurality of magazines on one side of the partition for holding articles, means for supporting the magazines with the delivery ends of the magazines equidistant from the partition, a coin controlled mechanism on the other side of the partition, means movable on two tracks parallel to the partition for supporting the coin controlled mechanism, means mounted in said coin controlled mechanism for ejecting an article from any one of the article magazines and ex-

tending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

14. In a store system, a partition having a U shaped part and a glass part provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, U shaped article ejectors joined together near their ends movable above the U shaped part and under the glass part, mounted in said coin controlled mechanism for ejecting an article from any one of the article magazines and extending through the slot in the partition; coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism in front of the penny ejectors, and a similar fixed rod in front of the nickel, dime and quarter ejectors, adjustable means mounted on said rods for engaging one or more of said hinged ejectors to thereby deflect the hinged ejectors out of operating position, means in said coin controlled mechanisms controlled by coins of different denominations for operating the article ejector and the hinged coin ejectors, and a delivery chute extending through the partition for receiving the article ejected from one of the article magazines and change ejected from one or more of the coin magazines.

15. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism,

means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, selectively adjustable means mounted on said rod for engaging one or more of said hinged ejectors to thereby deflect the hinged ejectors out of operating position, said means consisting of pegs, any one of which may be inserted in any hole in said rod, means in said coin controlled mechanisms controlled by coins of different denominations for operating the article ejector and the hinged coin ejectors, and a delivery chute extending through the partition for receiving the article ejected from one of the article magazines and change ejected from one or more of the coin magazines.

16. In a store system means by which articles may be seen but not taken except by operating a coin controlled mechanism, a partition provided with a slot; a plurality of magazines on one side of the partition for holding articles, means for supporting the magazines with the delivery ends of the magazines equidistant from the partition, a coin controlled mechanism on the other side of the partition, wheels on said mechanism adapted to run on the upper and lower side of a track parallel to the partition, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

17. In a store system, a partition provided with a slot; a plurality of magazines on one side of the partition for holding articles, means for supporting the magazines with the delivery ends of the magazines equidistant from the partition, a coin controlled mechanism on the other side of the partition,

- means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, a removable change chute attached to the coin controlled mechanism with its upper end extending under the center penny magazine and its lower end adjacent to the side of a chute located under some of the coin magazines, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position; means in said coin controlled mechanism controlled by coins of different denominations for operating the article ejector and the hinged coin ejectors, and a delivery chute extending through the partition for receiving the article ejected from one of the article magazines.
18. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, two removable extensions on stationary rods passing through the coin controlled mechanism so as not to interfere with the moving of said mechanism in a direction parallel with the said partition, any of said extensions selectively located on its rod so as to divert a forward moving coin ejector to a position where it will not eject a coin from its corresponding coin magazine when the coin controlled mechanism is in a predetermined position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.
19. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, two removable extensions on stationary rods passing through the coin controlled mechanism so as not to interfere with the moving of said mechanism in a direction parallel with the said partition, any of said extensions selectively located on its rod so as to divert a forward moving coin ejector to a position where it will not eject a coin from its corresponding coin magazine when the coin controlled mechanism is in a predetermined position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.
20. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging a coin ejector when the coin controlled mechanism is operated by a coin at a predetermined position in respect to the location of an article for purchase at a price not requiring a coin to be produced in change by said coin ejector from its corresponding coin magazine, but said coin ejector producing a coin when said coin controlled mechanism is operated at all other positions a spring holding the hinged ejectors in operating position,

means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

21. In a store system, a partition provided with a slot; a plurality of magazines on one side of the partition for holding articles, means for supporting the magazines with the delivery ends of the magazines equidistant from the partition, a coin controlled mechanism on the other side of the partition, said partition having its center section of U shape, its upper section partly of glass at right angles to the U section and in the same plane with its upper section but having an opening for an article chute through it, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, hinged ejectors mounted in said coin controlled mechanism for ejecting coins from the coin magazines; a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanisms controlled by coins of different denominations for operating the article ejector and the hinged coin ejectors, and a delivery chute extending through the partition for receiving the article ejected from one of the article magazines and change ejected from one or more of the coin magazines.

22. In a store system, a partition provided with a slot; a plurality of magazines on one side of the partition for holding articles, means for supporting the magazines with the delivery ends of the magazines equidistant from the partition; a coin controlled mechanism on the other side of the partition, means movable parallel to the partition for supporting the coin controlled mechanism, means mounted in said coin controlled mechanism for ejecting an article from any one of the article magazines and extending through the slot in the partition, coin magazines for holding change mounted in said coin controlled mechanism, one or more coin ejectors pivoted to forward moving parts of said coin controlled mechanism so as to allow their forward ends to be moved horizontally out of alignment with corresponding coin magazines, and having one end of a spring attached to each ejector and the other end

to the coin controlled mechanism, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanisms controlled by coins of different denominations for operating the article ejector and the hinged coin ejectors, and a delivery chute extending through the partition for receiving the article ejected from one of the article magazines and change ejected from one or more of the coin magazines.

23. In a store system, a partition provided with a slot; a plurality of magazines on one side of the partition for holding articles, means for supporting the magazines with the delivery ends of the magazines equidistant from the partition, a coin controlled mechanism on the other side of the partition, means movable parallel to the partition for supporting the coin controlled mechanism, means mounted in said coin controlled mechanism for ejecting an article from any one of the article magazines and extending through the slot in the partition, said means consisting of two rods joined together near their corresponding ends nearest the article magazines, said rods having a projection for raising an article and another projection, said rods shaped so that a section of each rod near the coin controlled mechanism will enter a corresponding slot in the partition when moved forward, coin magazines for holding change mounted in said coin controlled mechanism, hinged ejectors mounted in said coin controlled mechanism for ejecting coins from the coin magazines, a fixed rod mounted parallel to the partition and extending through said coin controlled mechanism, adjustable means mounted on said rod for engaging one or more of said hinged ejectors to thereby deflect the hinged ejectors out of operating position, means in said coin controlled mechanism controlled by coins of different denominations for operating the article ejector and the hinged coin ejectors, and a delivery chute extending through the partition for receiving the article ejected from one of the article magazines and change ejected from one or more of the coin magazines.

In testimony whereof I affix my signature. 120
WILLIAM HUNTINGTON RUSSELL.
